UNITED STATES PATENT OFFICE.

THEODORE P. GARANKIN, OF NEW YORK, N. Y., ASSIGNOR OF FIFTY PER CENT TO
LYDIA UTGOFF, OF NEW YORK, N. Y.

UMBRELLA OPENING AND CLOSING ATTACHMENT.

Application filed October 5, 1926. Serial No. 139,665.

My invention relates to umbrella opening and closing attachments and has a particular reference to attachments for operating locking devices on ordinary umbrellas and 5 parasols.

The object of my invention is to provide an attachment in the form of a sleeve loosely mounted on the lower sliding bushing of an umbrella in such manner that by turning 10 this sleeve one way or another the locking or unlocking of the sliding bushing can be accomplished automatically.

In the ordinary construction, in order to open an umbrella it is necessary to insert 15 one's finger between the ends of the umbrella ribs, to depress the spring lock with the finger and then to move the bushing with the ribs up until it is locked in an open position. These operations are accompanied 20 with certain inconveniences, the finger may be bruised or pinched, especially when releasing umbrella from the open position, gloves may be damaged etc.

With my attachment the release or depression 25 of the lock is performed by the sleeve which should be held in one hand, while the umbrella handle is turned by the other. The attachment sleeve depresses or releases the spring latch according to the direction of rotation of the sleeve.

My invention is more fully described in the accompanying specification and drawing in which—

Fig. 1 is a partial elevation of an umbrella with my attachment, Fig. 2 is an enlarged cross-sectional view taken on the line 2—2 of Fig. 1, Fig. 3 is an enlarged cross-sectional view taken on the line 3—3 of Fig. 1, Fig. 4 is an elevation of a modified 40 attachment, adapted to be applied to ordinary umbrellas, Fig. 5 is another modification, Fig. 6 is an enlarged cross-sectional view taken on the line 6—6 of Fig. 5, and Fig. 7 is an enlarged sectional elevation of 45 my attachment.

My attachment consists of an operating sleeve 1 loosely mounted on an umbrella sleeve or bushing 2, the latter being slidably mounted on a shaft 3 of an umbrella. The bushing 2 has a circular enlargement 7 on its upper portion with slots for the ends of umbrella bars 4 of an ordinary construction. The shaft 3 is provided with a slot 16 for a locking latch 5. This latch has a resilient 50 extension 15 of such shape that it tends to

force the operating portion of the latch out of the slot 16. With the umbrella fully folded the slot 13 of the bushing 2 registers with the slot 16 with the latch passing through both of these slots as can be seen 60 in Figs. 1, 2, 4, 5, 6 and 7. The straight lower edge of the locking latch prevents the bushing 2 from sliding upwards. The sleeve 1 is provided with an aperture 1'. One edge of this aperture is straight (shown on the 65 left side, Fig. 1) and the other is curved with an outwardly curved edge 6. The sleeve 1 has enlarged or flared out ends placed between the rings 7 on top and a flange 8 on the bottom of the bushing 2. 70 With this arrangement the sleeve 1 can be revolved on the bushing 2 moving with it up or down on the shaft 3.

The bushing 2 has a second slot 26 preferably at 90 degrees with the first slot 16 for 75 the upper locking latch (not shown) which serves to lock the umbrella in an open position.

In order to facilitate the turning of the sleeve 1 it may be provided with knobs or 80 buttons 10.

The proper operating position of the sleeve 1 on the bushing 2 is indicated by punched out resilient lugs 9 adapted to engage indicating holes 11 and 12 in the 85 shaft 3.

Instead of making separate holes 11 and 12 with a lug or tongue 9, two resilient tongues 9' may be provided, at 180 degrees from each other, located in the upper portion 90 of the sleeve 1. These tongues are adapted to register with the slot 16 in different respective positions.

The operation of my attachment is as follows:

The umbrella handle 14 is held in one hand and the sleeve 1 in the other. The handle is then turned in a direction of an arrow 14' until the tongue 9 registers with the hole 11 (or tongue 9' with the slot 16). During 100 this rotation the rounded or raised edge 6 of the sleeve 1 slides over the inclined edge of the latch 5, thereby forcing it inside of the tubular shaft 3. The bushing 2 with the sleeve 1 is then free to be moved up until the umbrella is fully open in which position the upper spring latch (not shown), identical in construction with the latch 5, engages the slot 26. In this position the opening 1' 105 is located opposite the slot 26 leaving the 110

upper latch free to engage the slot 26. In the order to fold or to close the umbrella the sleeve 1 is held in one hand and the handle 14 in the other and the latter turned against the arrow 14'. The lower portion of the edge 6 will then slide over the inclined edge of the upper latch thereby forcing the latter inside and releasing the sleeves 2 and 1.

A modified arrangement is shown in Fig. 4, which may be used for ordinary types of umbrellas. The sleeve 17 is open on one side so that it can be forced over the bushing 18. For this purpose it should be preferably made of a resilient material such as spring steel. It may be provided with a circular groove to fit over the lower web 19' of the bushing 18. This groove and the rings 7 will prevent the sleeve 17 from sliding off the bushing 18.

In case when the web 19' is too small to hold the sleeve 17, a circular clamp 20 may be provided. It consists of two halves joined together with screws 22 in the lugs 23. Hooks 21 extend over the edges of the rings 7. The clamp fits over the upper flange 27 of the sleeve 17 keeping it in engagement with the bushing 18 but at the same time allowing it to rotate on the bushing 18.

Another modification is shown in Fig. 5. Here the sleeve 24 is provided with a curved and outwardly extending pocket 25 adapted to cover the latch 5. The pocket 25 extends also on the other side of the latch with a curved lip 28.

The operation of this modification is substantially the same as with the other forms

disclosed, but in depressing the latch 5 the middle portion of the pocket acts on the highest point of the latch 5, gradually bringing it down into the hollow of the shaft 3, when the handle 14 is turned and the sleeve 1 held stationary.

Important advantages of my attachment are that it can be used with ordinary umbrellas and facilitates the manipulations of opening the umbrella and of closing or folding it. It provides intermediate means for acting on the umbrella spring latches thereby relieving the user of the umbrella from the necessity to use fingers in depressing the latches.

I claim as my invention:

In an umbrella opening and closing attachment, the combination with a straight tubular member forming an extension of an ordinary runner of an umbrella and slidably fitted over the umbrella stem, said tubular member being provided with a longitudinal slot for a spring latch mounted inside of said umbrella stem, and a second straight tubular member rotatively fitted on said first member and adapted to depress said latch inside of said stem thereby rendering same inoperative, and an outwardly extending pocket at one side of said outer tubular member, said pocket being adapted to receive said latch thereby rendering same operative.

Signed at New York, in the county of New York and State of New York.

THEODORE P. GARANKIN.
